UNITED STATES PATENT OFFICE.

HOSEA W. LIBBEY, OF BOSTON, MASSACHUSETTS.

BICYCLE.

SPECIFICATION forming part of Letters Patent No. 530,540, dated December 11, 1894.

Application filed December 16, 1893. Serial No. 493,849. (No model.)

To all whom it may concern:

Be it known that I, HOSEA W. LIBBEY, a citizen of the United States, residing at Boston, in the county of Suffolk and State of Massachusetts, have invented certain new and useful Improvements in Bicycles, of which the following, taken in connection with the accompanying drawings, is a specification.

My invention relates to certain improvements in the propelling mechanism for bicycles and the invention consists of a divided axle each portion of which is operated to propel the wheel forward by means of a lever operating a belt or strap wound around a drum secured to the outer end of each portion of the axle to which drum one end of said strap is attached, the other end being attached to the said operating lever and a series of pawls attached to a divided hub, each section of the axle being provided with depressions or recesses into which said pawls fall, a volute spring being attached at one end to the drum carrying the operating strap and the other end of said spring being attached to a box or casing secured to the frame so that when the operating lever has been depressed to rotate one shaft section, the volute spring will cause the strap to be again wound upon the drum ready for a further operation all as hereinabove described and pointed out in the claims.

Referring to the accompanying drawings:—Figure 1—represents a side view of a bicycle embodying my invention. Fig. 2— is a section taken through the divided hub, frame, bearings, and boxes, the divided axle being shown in side elevation. Fig. 3— is a side view of the same. Fig. 4— is a cross section taken on line w, w , of Fig. 2. Fig. 5— is a similar section taken on line x, x , of Fig. 2. Fig. 6— is a cross section taken on line y, y , of Fig. 2, and Fig. 7— is a cross section taken through the frame bearing on line z, z , of Fig. 2.

A represents the front wheel, B the rear or driving wheel, and C the frame, which may be of ordinary construction.

The axle of the driving wheel is formed in two parts D, D', (see Fig. 2) the inner ends of which are fitted with collars d, d' , that are free to revolve thereon. These sectional portions of the axle are held together by a divided hub E, bolted together on each side as

will be best seen in Figs. 3 and 4. This divided hub E, is formed with two projections e, in which are mounted pawls F, that take or fall into recesses or notches d' , formed in each of the portions of the divided axle as shown. See Figs. 2 and 4. At the outer end of each portion of the divided axle is secured a partitioned drum G, to one part of which is secured one end of a strap or belt H, the other end of which is attached to one of the operating levers I, fulcrumed at i, to the frame C. The outer end of each of these levers is provided with a pivoted foot rest J.

To the inner portion of the drum G, is secured one end of a volute spring K, the other end of which is attached to a box or casing L, secured to the frame of the machine which box or casing also incloses the drum G, and protects it from dust and dirt, and in the upper part of the box or casing L, is an opening l, through which the strap or belt H, passes a friction roller k, being fitted on one side of the said opening to prevent the wearing of the strap H, as it is drawn out and in.

The lower ends of the rear fork of the frame are fitted with boxes M, in the upper portion of which are placed balls m, that rest upon the axle D, D', to reduce friction.

The operation is as follows: The rider depresses the front ends of the lever I, alternately. As one of said levers is depressed its rear end is raised and draws upon the strap H, and unwinds it from the drum G, which being secured upon one of the sections D, D', of the axle causes said section to be rotated. One or more of the pawls F, on the divided hub E, falling into one or more of the recesses d' , in the axle section causes the wheel to be rotated. The rider then raises his foot and the volute spring K, causes the said axle section to be rotated in the opposite direction thereby again winding the strap H, upon the drum G, ready for another propelling action.

As one of the levers I, is being depressed the other is being raised so that one or the other of the axle sections is rotated to drive the wheel while the other section is rotated by the volute spring in the opposite direction, so that there is always a propelling force being exerted upon the divided hub of the wheel and momentum retained.

Although I have described and shown my

invention as applied to a bicycle it is obvious that it could be applied to other kinds of road vehicles.

What I claim is—

- 5 1. In a bicycle an axle divided in the center of its length and having collars at the inner end of each section said collars bearing against each other and a hub divided longitudinally and having annular recessed projections, pawls mounted in said recesses and ratchet teeth on the axle sections for said pawls and means for alternately rotating said axle sections as set forth.
- 10 2. In a bicycle a single hub divided longitudinally and inclosing an axle divided in the center of its length, collars mounted upon the inner ends of said axle, two series of pawls arranged in the divided hub near the inner ends of each section of the axle, ratchet teeth upon each of said axle sections in combination with drums mounted upon the outer end of said axle sections, a strap wound thereon the outer end of which is attached to an op-

erating lever and a volute spring for rewinding the strap upon the drum substantially as set forth.

- 25 3. In a bicycle an axle formed in two parts D, D', collars d, d', secured on their inner ends, a longitudinally divided wheel hub E, pawls F, arranged therein, ratchet teeth d², 30 cut in the axle section, a drum G, on the outer end of each axle section, straps H, secured at one end to said drums G, the outer ends being attached to operating levers I, fulcrumed to the frame of the machine, and volute springs K, for rewinding said straps H, upon the drums G, substantially as shown and described.

In testimony whereof I have signed my name to this specification, in the presence of 40 two subscribing witnesses, on this 27th day of April, A. D. 1893.

HOSEA W. LIBBEY.
